VALVE ASSEMBLY

Harry V. Haight, Corning, N. Y., assignor to
Ingersoll-Rand Company, Jersey City, N. J., a
corporation of New Jersey

Application May 10, 1932, Serial No. 610,508

2 Claims. (C.I. 277—60)

This invention relates to valves for blowing engines or compressors.

It has for its object to provide a valve assembly for a compressor which is durable and not complicated. The invention will be understood by reference to the following description taken in conjunction with the drawings in which,

Fig. 1 is a cross sectional view through a valve assembly constructed in accordance with the practice of the invention,

Fig. 2 is a similar view taken at right angles to Fig. 1,

Fig. 3 is a section taken along the line 3—3 of Fig. 2 looking in the direction of the arrows,

Fig. 4 is a section through the stop plate of the valve assembly,

Fig. 5 is a cross section of a modification of the invention,

Fig. 6 is a cross section of another modification of the invention,

Fig. 7 is a cross section of still another modification of the invention,

Fig. 8 is a transverse view taken through Fig. 7 on the line 8—8, and

Fig. 9 is a cross sectional view taken along the line 9—9 of Fig. 7 looking in the direction of the arrows.

Referring to the drawings and more particularly to the embodiment shown in Figs. 1 to 4 inclusive the valve assembly comprises a valve seat 10 consisting of a plate of uniform thickness throughout and having a plurality of ports 12 in this instance arranged parallel to each other, each port being a rectangular slot formed in the seat. The upper face 14 of the seat 10 is in this instance a plane surface upon which are adapted to seat a plurality of valves 16 overlying the ports 12. Each port 12 is controlled by a separate valve 16 each acting independently of every other valve.

Each valve 16 consists of a strip of material, such as steel, and is of rectangular form relatively long with respect to its width and is sufficiently stiff so that it lifts from the seat bodily and without substantial bending. At their ends the valves 16 are guided by a distance piece 18 preferably having a circular periphery like that of the valve seat 10, said distance piece being of uniform thickness throughout and having flat end surfaces. The interior of the distance piece 18 is provided with notches 20 to conform with the shape of the ends of the valves 16 but somewhat larger, to allow the valve ends to lift freely.

As is shown in Fig. 1 the distance piece 18 is superimposed on the upper face 14 of the valve seat 10, and on top of the distance piece 18 a stop

plate 21 is mounted. The stop plate 21 in this instance has flat end faces and has an outer continuous edge as shown at 22 across which extend bridging portions 24 which overlie and register with the valves 16. Preferably the stop plate 21, the distance piece 18 and the seat 10 are rigidly held together as by means of the screws 26.

The valves 16 are of the voluntary type, that is, they are adapted to be raised from their seats by the pressure of the fluid at the ports 12. They may be returned to their seats by any suitable means, preferably of the spring type. Three types of such springs are shown in Figs. 2, 5 and 6. In Fig. 2 a long leaf type spring 28 is interposed between the bridging members 24 and the valves 16 contacting with the former at approximately the center and bearing against the valve 16 at the tips. The springs 28 are held in position by the notches 20 in the distance piece 18. In Fig. 5 is shown a spiral form of spring 30 which is seated in recess 32 in the stop plate 21.

If desired a spring of the form shown at 34 in Fig. 6 may be utilized. Spring 34 has a double bend to contact at two places 36 on the valve 16 rather remote from the ends of the valve to prevent bending thereof and is guided at the tips of the spring in the notches 20 of the distance piece 18.

In the operation of the device shown in Figs. 1 to 6 the compressed fluid entering the ports 12 raises the valves 16 against the tension of the springs 28, 30 or 34 as the case may be, lifting the valves bodily without essential bending, the amount of the lift being dependent upon the thickness of the distance piece 18. The motive fluid passing the valves 16 passes through the valve assembly at the space between the bridging members 24 and is discharged therefrom. This form of valve assembly has the advantage that all of the pieces except the springs have flat faces which can be easily machined and manufactured. The valves 16 are not adapted to bend and consequently have relatively long life. The faces of the valves are easily machined, being flat to seat upon the flat face 14 of the seat 10 and are relatively inexpensive.

The embodiment shown in Figs. 7 to 9 inclusive shows the valve assembly which is arranged to provide more port area than that above described. This arrangement includes a cage 50 generally cylindrical which is provided with a shoulder 52 to abut a corresponding shoulder 54 in a recess 56 of a compressor cylinder wall. A plurality of ports 58 are provided lengthwise of the cage 50

and on the interior of the cage are provided flat seats 60 upon which are adapted to seat valves 62 similar to the valve 16. For each valve separate distance pieces 64 are provided at the ends 5 of each port 58 and in each distance piece is a notch 66 similar to the notches 20 to guide the valves 62 at their ends only. The stop plates in this arrangement consist of flat strips of metal 68 in this instance riveted as at 70 to the distance 10 pieces 64. The valves 62 are rigidly held to the seats 58 by means of springs 72 similar in function to the springs 28. The stop plate 68 and the distance pieces 64 are fastened to the seat 60 by means of screws 74.

15 To prevent the assembly from providing too much cylinder clearance the interior is partially filled by a plug 76 having a flanged end 78 to cooperate with a counter-bore 80 in the cage 50.

The arrangement above described is arranged 20 as an inlet valve for a cylinder 82 of which the piston 84 is partially shown as well as the cylinder head 86. In this instance the cage 50 fits into the aperture 56 of the cylinder wall and extends across the inlet space 88 and partially 25 through the outer wall 90 which is closed by a suitable cap 92 enclosing the valve assembly. The valve assembly is held tightly in place by a jack screw 94 threaded in the cap 92 and adapted to bear against the center of the rear end of the plug 76 at the intersection 96 of the bridging members 98. When being inserted the proper centering of the valve assembly is assured by means of screws 100 in the cage 50 which are adapted to slide in slots 102 in the outer wall 90.

30 The cage 50 is clipped in place by means of a

spring member 104 on the periphery of the cage which is adapted to spring out of place when the cage is being inserted and to grip the wall at a bend 106 in the spring.

Thus by the above construction are accomplished, among others, the objects hereinbefore referred to.

I claim:

1. A valve assembly comprising a cylindrical member having a plurality of ports arranged lengthwise therein, seats at the ports, rigid flat plate valves cooperating with the ports, springs for holding said valves resiliently to the seats, separate distance pieces at the ends of each port mounted on said cylinder, of uniform thickness throughout and having notches to guide the valves only at their ends, and stop plates of uniform thickness throughout mounted on said distance pieces and arranged to confine the springs and the valves.

2. A valve assembly comprising a cylindrical member having a plurality of ports arranged lengthwise therein, seats at the ports, rigid flat plate valves cooperating with the ports, springs for holding said valves resiliently to the seats, 15 separate distance pieces of uniform thickness throughout mounted on said cylinder adjacent the ends of each port and having notches to guide the valves only at their ends, stop plates of uniform thickness throughout mounted on said distance pieces and arranged to confine the springs and the valves, and a spring clip on the periphery of the cylindrical member for holding said cage in a compressor cylinder.

HARRY V. HAIGHT. 35

CERTIFICATE OF CORRECTION.

Patent No. 1,986,810.

January 8, 1935.

HARRY V. HAIGHT.

It is hereby certified that error appears in the printed specification of the above numbered patent requiring correction as follows: Page 2, lines 14, 15 and 16, claim 1, strike out the words "at the ends of each port mounted on said cylinder, of uniform thickness throughout" and insert instead of uniform thickness throughout mounted on said cylinder at the ends of each port; and that the said Letters Patent should be read with this correction therein that the same may conform to the record of the case in the Patent Office.

Signed and sealed this 26th day of February, A. D. 1935.
